UNITED STATES PATENT OFFICE.

MAX TURUDICH, OF STEUBENVILLE, OHIO.

SOUNDING TOY.

Application filed March 1, 1927. Serial No. 171,811.

This invention relates to a sounding toy, and has for its object to provide, in a manner as hereinafter set forth, a toy of such class capable of automatically creating a noise or rattle to startle or scare the person opening or releasing the toy thereby affording considerable amusement and further whereby the device can be employed for advertising and other purposes.

10 Further objects of the invention are to provide, in a manner as hereinafter set forth a sounding toy which is simple in its construction and arrangement, strong, durable, compact, conveniently set in non-released position, amusing in its use, and inexpensive to manufacture.

With the foregoing and other objects in view the invention consists of the novel construction, combination and arrangement 20 of parts as hereinafter more specifically described and illustrated in the accompanying drawings wherein is shown an embodiment of the invention, but it is to be understood that changes, variations and modifications 25 can be resorted to which fall within the scope of the claims hereunto appended.

In the drawings wherein like reference characters denote corresponding parts throughout the several views:

30 Figure 1 is a sectional plan of a sounding toy in accordance with this invention.

Figure 2 is a longitudinal sectional view thereof.

Figure 3 is a cross sectional view.

35 Figure 4 is a cross sectional view with the toy in released position.

Figure 5 is a fragmentary view of a modified form of rotating means for the combined sounding and detonating element.

40 A toy in accordance with this invention includes a normally latched spring controlled, rotatable combined sounding and detonating element interposed between and coacting with a pair of sound creating elements, preferably thin metallic plates, carried by and providing linings for the inner faces of a pair of normally closed, hinged base members, which when opened automatically release the sounding and detonating element.

45 50 for coaction with the sound creating elements to create a noise or rattle and for further causing the detonation of a pair of explosive caps carried by the sound creating elements. The toy may be set up in various forms, such as the representation of a book, foldable post card, envelope, etc., and by way

of example the toy is set up as the simulation of a book. It is to be understood, as aforesaid, that the toy can be of any suitable form as desired.

As illustrated the toy includes a pair of base members 1, 2, the latter being in the form of an open top rectangular receptacle provided upon the inner face of its bottom with a lining 3, in the form of a thin metallic plate, and which constitutes a sound creating element. The base member 1 at its ends and one side edge is flanged as at 4 for overlapping the base member 2, see Figure 3. The base member 1 is hinged to the base 60 member 2 as indicated at 5. The inner face of the base member 1 is provided with a lining 6, formed of a thin metallic plate and which constitutes a sound creating element. When the toy is closed the linings 3 and 6 65 oppose each other, see Figure 3. The base member 1 or the base member 2 can be the top of the toy when the latter is handed to one for the purpose of opening the toy, and on the opening movement thereof the combined sounding and detonating element to be presently referred to, will be released and its co-action with the linings 3 and 6 will 70 create a noise or rattle to startle, frighten or scare the person opening or releasing the 75 device. Secured to the lining 3 is a pair of keepers 7, 8 arranged in proximity to the ends of said lining and which provide means for pivotally connecting a carrier 9 therewith. The carrier 9 is of yoke-shaped contour and includes a longitudinally disposed base 10 and a pair of horizontally disposed arms 11, 12 each having its free end provided with a hook 13. Preferably the body portion 80 of the carrier 9 is of cylindrical cross section 85 and not only provides means for carrying the combined sounding and detonating element and the rotating means for the latter, but also couples said means and element to the lining 3. The carrier 9 has its base 10 90 positioned in proximity to one side edge of the lining 3 and the arms 11, 12 of the carrier 9 extends towards the other side edge of the lining 3 and the hooks 13 are positioned approximately centrally of said lining.

100 The combined sounding and detonating element is indicated at 14 and is in the form of an annulus of appropriate diameter, constructed preferably of metallic material and 110 having its body portion of cylindrical cross section. The element 14 is disposed cen-

trally with respect to the base members and connected at diametric points thereof is a pair of oppositely extending rotating members for the element 14. The said rotating elements for the element 14 are indicated at 15, 16 and as shown in Figures 1 to 4, each of said elements consists of a rubber band having its inner end connected to the element 14 and its outer end attached to an arm 10 11 or 12 and maintained in position by the hook 13. The elements 15 and 16 are twisted to tension them to the desired degree and after such action the base members are closed and the elements of the toy will be as shown 15 in Figures 2 and 3. When one of the base members is moved from the other or when the base members are released relative to each other, the expansion of the elements 15 and 16 will provide for the rotating of the 20 element 14 and the latter riding against the linings 3 and 6 will create a noise or rattle and under such conditions startle or scare the person holding the toy.

Each lining is slotted as at 17 and the 25 material freed by the slit provides a fastening barb for detachably securing an explosive cap 19 to the lining and which is in the path of the sounding and detonating element 14. The cap 19 is positioned at the transverse median of a lining and intersects the longitudinal median thereof. By this arrangement when the base members are released relatively to each other, after the elements 15 and 16 have been twisted to provide for the desired tension therefor, the element 14 as it is rotated by the elements 30 15 and 16 will swipe or wipe the caps 19 and cause the explosion thereof, under such conditions the element 14 not only coacts with the linings 3 and 6 to create a sounding automatically, but also provides for exploding the caps which will further act to startle or scare the person holding the toy.

The form shown in Figure 5 is the same 45 as that illustrated in connection with the form shown in Figure 1 with this exception that the rotating elements for the combined sounding and detonating element 14 are in

the form of coil springs as indicated at 20. Otherwise than that as stated the construction of the device with respect to Figure 5 would be the same as that shown in connection with Figures 1 and 2.

Although the preferred embodiment of the invention is as illustrated and described, yet 55 it is to be understood that changes in the details of construction can be had which will fall within the scope of the invention as claimed.

What I claim is:

1. A sounding toy comprising a pair of normally closed, hinged base members, a lining for each of said members and providing a sound creating element, a normally tensioned, automatically rotatable sounding element interposed between said linings and releasable for rotation on the opening of the base members relatively to each other, said element pivotally connected with one and co-acting with both linings during its rotation for creating sound, and each of said linings provided with means for positioning an explosive cap in the path of said element for detonation thereby during the operation thereof. 75

2. A sounding toy comprising a pair of hinged sound creating elements opposing each other, a yoke shaped carrier pivotally connected to one of said elements and opposing the inner face thereof, a sounding element positioned between said sound creating elements, resilient elements connecting said sounding element to the arms of said carrier and capable of being tensioned to provide, when released, the rotating of and the impacting of the sounding element against said sound creating elements, and each of said sound creating elements provided with means for detachably connecting an explosive cap in the path of rotation of the sounding element to be detonated by the latter. 80 85 90

In testimony whereof, I affix my signature hereto.

MAX TURUDICH.
